United States Patent Office.

WILLIAM S. COLWELL, OF ALLEGHENY CITY, PENNSYLVANIA.

Letters Patent No. 83,466, dated October 27, 1868.

IMPROVEMENT IN STAVE-MACHINES.

The Schedule referred to in these Letters Patent and making part of the same.

To all whom it may concern:

Be it known that I, WILLIAM S. COLWELL, of the city and county of Allegheny, in the State of Pennsylvania, have invented a new and useful Improvement in "Rams" for Stave-Machines; and I do hereby declare that the following is a full, clear, and exact description thereof, reference being had to the accompanying drawings, and to the letters and figures of reference marked thereon.

The nature of my invention consists in providing the "ram" of stave-machines with a rack, and combining therewith a series of wheels, for imparting to said "ram" a reciprocating motion, the whole being constructed, arranged, and operating in the manner hereinafter described.

To enable others skilled in the art of constructing stave-machines to make and use my improvement, I will proceed to describe its construction and operation.

In the accompanying drawings, which form part of my specification—

Figure 1 is a top view of my improvement in "rams" for stave-machine.

Figure 2 is a side elevation of the same.

In the drawings, A represents the frame, connected with the ram.

The ram B is made in any of the known forms, and is provided with a T-head, D, which moves in slides C.

To the back part of the ram B is secured a rack, marked e, which is provided with a detachable and an adjustable tooth, x.

Into the rack e gear two wheels, f and i, the wheel i having teeth on only part of its periphery.

On the shaft 2, above wheel f, is a wheel, g, which gears into the wheel h, which has teeth on only part of its periphery, and is placed above the wheel i, on shaft 3.

The tooth x of the rack e is made detachable and adjustable, for the purpose of adjusting said tooth to the gear of wheels h and i, and for removing said tooth when it becomes worn out, said tooth being subjected to the greatest wear and friction.

The stop n is used for the purpose of preventing the ram from being thrown too far forward, and thus placing wheels and rack e out of proper gear.

As the construction and arrangement of the several parts will be clearly seen by reference to the accompanying drawings, I will, without further description of their construction, proceed to describe the operation, which is as follows: By turning the shaft 3, the wheel h will revolve the wheel g, and shaft 2 and wheel f, which will move forward ram B, until the teeth of the wheel h pass out of gear with the teeth of wheel g. By this time, the teeth of wheel i will come into gear with the teeth of the rack e, and will force back the ram B. By this time, the teeth of wheel h will come into gear with wheel g, which will revolve it, and the shaft 2 and wheel f, which will again move the ram forward. And thus will the wheels, in connection with the rack, continue to impart a reciprocating motion to the ram, without the use of cords, weight, or spring, which are now used for drawing back the ram.

Having thus described the nature, construction, and operation of my improvement,

What I claim as of my invention is—

The combination of the wheels f, g, h, and i, with the rack e, for imparting a reciprocating motion to the ram B, substantially as herein described and set forth.

W. S. COLWELL.
